(57) **CLAIM**

The ornamental design for a bunk bed as shown and described.

DESCRIPTION

FIG. 1 is a top, front perspective view of a bunk bed showing my new design;

FIG. 2 is a bottom, rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged view of portion 9 shown in FIG. 1;

FIG. 10 is an enlarged view of portion 10 shown in FIG. 1;

FIG. 11 is an enlarged view of portion 11 shown in FIG. 1;

and,

FIG. 12 is an enlarged view of portion 12 shown in FIG. 2.

The dot-dash broken lines represent boundaries of the

enlarged portions and form no part of the claimed design.

1 Claim, 12 Drawing Sheets
